UNITED STATES PATENT OFFICE.

ROBERT B. McGOWAN, OF CINCINNATI, OHIO.

GOVERNING DEVICE.

SPECIFICATION forming part of Letters Patent No. 786,984, dated April 11, 1905.

Application filed December 13, 1904. Serial No. 236,736.

To all whom it may concern:

Be it known that I, ROBERT B. McGOWAN, a citizen of the United States, residing at Cincinnati, in the county of Hamilton and State of Ohio, have invented new and useful Improvements in Governing Devices, of which the following is a specification.

My invention relates to two classes of governors: first, those for pumps used in raising water, compressing air, &c., operating against a head or pressure where the pressure is utilized to regulate and control the supply of steam or other motive power to the motive machinery, and, second, those adapted to regulate the pressure of steam, liquids, air, or gas within a pipe-line, in which case the mechanism at the receiving end of the device is connected with and operates to control and regulate the passage of steam, air, gas, or liquids through the delivery end of the device, and constitutes an improvement upon the invention shown in Letters Patent No. 730,682, issued to me June 9, 1903.

My improved device illustrated and described herein has certain advantages over the earlier type, whereby, first, the spring used to secure regulation of pressure is removed from contact with corrosive elements by placing in a dry separate case; second, through the lever and its attendant parts is secured a greater scope of pressure regulation and quick easy readjustment of the same. These tend to secure most positive and perfect action, wider range of efficiency, added durability, economy and simplicity of construction, and ease of adjustment.

Part of the improvements constituting this invention may be used advantageously independently or doubly in combination in all constructions where such mechanism might be useful, as in ordinary steam-governors, pressure-regulators, &c.

My invention is illustrated in the accompanying drawings, in which—

Figure 1 is an exterior elevation of my improved governing device complete. Fig. 2 is an elevation with parts broken away to show all necessary working parts in axial section.

Fig. 3 is a perspective view of the forked end of the lever with attendant valve-stem in section and shows depression in lever adapted to receive pivot. Fig. 4 is a sectional elevation of the governor-chamber detached. Fig. 5 is a corresponding perspective view of the cylindrical throttle-valve detached. Fig. 6 is an adjustable pivot-point and lock-nut. Fig. 7 is an elevation of a portion of the lower part of the spring-case and means of securing same to the lever and bar, with said lever, bar, and the cross-head in section. Fig. 8 is an axial section of the cross-head that is set on the stem.

In the particular embodiment of my invention selected for illustration in the drawings, A designates the governor-chamber, containing a throttle-valve B, and a a governor-body cap, with a', the upper valve-stop, cast thereon.

C designates a yoke-frame swiveled at its lower connection-plate c, so as to turn freely upon the cap a, or rather the boss a⁶ thereon. Said yoke and its connection is held in swiveling position to governor-chamber by set-screw v. The yoke terminates at the top in a plate c', which has rigidly attached to it the pressure-cylinder D, which is provided with a piston E operating therein. This piston is attached to the upper portion of the valve-stem F, which extends downward past the flange d of the pressure-cylinder D; the yoke-plate c', the swivel gland-packing nut G, which is threaded into the plate c'; the swivel gland-packing nut G', which is threaded into the cap a, the plate c; the boss a⁶, cap a, its valve-stop a', and the throttle-valve B. The stem F at a point between G and G' is operatively connected with a lever H, preferably by having said lever so placed that its fork h extends on each side of a circumferentially-grooved cross-head f, adapted to be adjusted at any point on the stem F. One or more set-screws f² secure the cross-head f to the stem F, and the cross-head movably connects the lever H and the stem F. The stem F throughout the portion that extends through the valve B is preferably reduced in

circumferential size to provide a shoulder f'' , upon which a washer I seats, against which the valve B seats. The valve B is held in place by the washer I', the nut J, and the lock-nut J'.

The governor-chamber A has a wall a^2 , hollowed cylindrically to form an opening for the vertical movement of the valve B. This wall, which for facility in casting I prefer to make of a separate shell and force or thread into position, has vacant zones a^3 , so arranged as to be capable of registering with the similar zones b in the valve B. The number and arrangement of these zones may be changed to accord with the travel and regulation desired. The inlet-port is designated as A' and the exit-port as A².

On the wall of the governor-chamber near the upper end of the exit-port A² is an extension of said wall, a^5 , which acts as a lower stop for the throttle-valve B.

The side wall a^4 of the governor-chamber A is continued around the shell a^2 to form an annular passage for the steam-supply and is provided with an aperture X, controlled by a by-pass valve K, which makes it possible to admit steam to the pump independently of the governor for "warming up" before starting and to accumulate pressure that the governor may resume its regulation without readjustment when set to close on complete diminution of pressure.

The throttle-valve B is constructed as follows: It is in the form of a cylindrical shell b' , partially cut away circumferentially into zones b , through which steam admitted through a^3 finds free passage through the exit-port A². Two or more radial arms b^2 connect the cylindrical shell b' and the axial socket or hollow stem b^3 . A radial-disk connection b^4 may be used to add rigidity to the valve, and this disk partition will be pierced with drain-holes b^5 .

The pressure-cylinder D has at its lower end and beneath the actuating-piston E an inlet-aperture d^2 , connected to the tank or delivery-column, (not shown,) the flow from which may be regulated by the globe-valve L.

An outlet-aperture d^3 , connected to an external aperture and waste-pipe d^4 , is governed by a direct-seating valve d^5 . The pressure-cylinder D is provided with a drain-passage D² outside the cylinder-chamber, which is connected with the cylinder-chamber above the piston E by a perforation d^6 to take off any accidental leakage past the piston E and to prevent back pressure caused by an accumulation above the piston of whatever is being fed to pressure-cylinder.

The screw-cap forming the top of the pressure-cylinder is designated as D³ and is loosely pierced axially by the upper extremity of the stem F. The length of the stroke of the valves is regulated by screwing the valve-

stop M up or down on the upper threaded extremity of the stem F, and the said stop is secured in any desired position by the lock-nut N.

Through one side of frame of the yoke C is an opening c^2 , through which the lever H passes and where it is pivoted by pivot O to permit of its vertical oscillation. The pivot is preferably formed of set-screws o, whose inner ends are conical in shape to fit corresponding depressions h' in the lever H. When these screws are adjusted, they are held in position by lock-nuts o'. Preferably above the opening c^2 , on the side frame of the yoke, is projected, preferably at right angles to said yoke-frame, a bracket C², having vertical slot c^3 .

Slidably adjustable upon and removable from the bar C² and the lever H is a telescopic compressible spring-case P and connections. The lower portion of this case P' is tubular, with an extension adapted to fit the slot c^2 , is finished cylindrically, and threaded at its lower end. P' also has, preferably, the edge of its upper end chamfered to avoid catching contact with any of the spring-coils. Into this portion P' of the case P is placed a suitable coiled spring Q, and the upper tubular portion P² of the same case P is placed over it, so as to shut down over P' telescopically. The upperend of P² is pierced axially to allow entrance of the hollow compression-screw R, upon which and within P² a swivel-plate r is held in position by nut r', and upon the under side of plate r the spring Q seats. The compression-screw is raised or lowered by means of the hand-wheel R' and is held in any desired position by the lock-nut R². An interior guide-bar y, fixed to the bottom of P', is preferably extended upwardly through R and secures the vertical movement and telescoping of the spring-case. By trunnions p, projected from the exterior of the lower end of P², are depended shackles T, whose lower ends are pivoted to the cross-head U by thumb-screws t, which hold cross-head in position at any desired point along the lever H and permit free upward and downward movement of the lever.

The shackles provide for the travel of the cross-head off the perpendicular line, due to the arc described by the movement of the lever, without effecting the direct vertical movement of the spring-case.

Ordinarily the spring-case P and the cross-head U are set, preferably, at a point on the lever corresponding to the distance represented between the center of the valve-stem and the lever-fulcrum, but may be set without readjustment at any point throughout the length of the bracket affording a range of pressures greater than that required for regular service. Thus, for example, perfect regulation is secured in waterworks plants during fire-service, when the liability of break-

ages in the distributing system is the greatest, thus safeguarding the pumping machinery at the most critical time.

In the accompanying drawings the parts are shown with the throttle-valve B depressed, there being insufficient head or pressure in the pressure-cylinder D to overcome the tension of the spring Q. When there is such an amount of pressure against the under side of the piston E, then said piston will rise, carrying with it stem F and forked end of lever H, thus depressing the outer end of lever H and compressing the spring Q. The stem F in rising will carry with it the throttle-valve B, admitting steam through a^3 , b, and A^2 to the engine. By proper regulation of the adjustable parts it is obvious that the device may be set to maintain the pressure necessary.

If the pressure in cylinder D is excessive, the piston E will rise, carrying stem F and valve B until said valve is carried upward far enough so that the steam is again shut off, thus avoiding danger to mechanism when one class of breakages occur.

On decrease of pressure the spring-pressure overbalances the water-pressure, and the upward movement of lever H and corresponding depression of valve-stem F and all attendant parts result to the point of cut off. These two forces operating upon the device should be adjusted to balance, so as to maintain a desired working pressure. The adjustment of the spring tension and the setting of the valve-stop is effected in a manner similar to that in my former patent referred to.

Obviously changes may be made, such as admitting steam or other pressure above the piston E and placing the bar C^2 beneath the lever and inverting the spring mechanism and many changes of like effect, without departing from the spirit of the invention.

I claim as my invention and desire to secure by Letters Patent of the United States—

1. In a governing device of the character indicated, the combination of a governor-chamber and a throttle-valve therein, a throttle-valve stem, extended as a piston-rod, a piston on said extended stem operating one way within a pressure-cylinder, said cylinder adapted to receive pressure, an adjustable spring located at a point outside of and not in contact with the contents of the pressure-

cylinder, a case inclosing the spring and composed of telescoping sections, means for operatively connecting said valve-stem and the movable member of the spring-case whereby the spring is actuated to secure pressure opposite that against the piston in the pressure-cylinder, substantially as set forth. 55

2. A pump-governing device embodying a throttle-valve adapted to register at normal pressure and to shut off at cessation or excess of pressure, said valve having its operating-stem extended as a piston-rod into a pressure-cylinder, a piston upon said rod actuated in said cylinder in one direction only by the resistance head or pressure, a lever movably attached to said valve-rod, said lever fulcrumed to a fixed point in said device, an adjustable spring adapted to actuate the piston valve-rod in the direction opposite the movement caused by the pressure and swiveling supporting means for the spring, the pressure-cylinder and the lever, substantially as set forth. 65

3. In a pump-governing device of the character indicated the combination of a governor-chamber and a throttle-valve therein, a throttle-valve stem extended as a piston-rod, a piston on said extended stem operating one way within a pressure-cylinder said cylinder adapted to receive pressure, an adjustable spring located at a point outside of and not 80 in contact with the contents of the pressure-cylinder and means for operatively connecting said valve-stem and said spring to secure pressure opposite that against the piston in the pressure-cylinder, and all the mechanism without the governor-chamber, swivelly connected to said governor-chamber, substantially as set forth. 85

4. In a pump-governing device of the character indicated, the combination of telescopic 95 spring-case, P, the spring, Q, the adjusting mechanism, the shackles, T, the cross-head, U, the bracket, C^2 , and means for pivotally securing said shackles to said spring-case and cross-head, substantially as set forth. 100

In testimony whereof I have hereunto set my hand in presence of two subscribing witnesses.
